UNITED STATES PATENT OFFICE

2,423,740

MEANS FOR ASSEMBLING THE BODY AND
BUTT OF AUTOMATIC FIREARMS

Josef Vesely, Winchmore Hill, London, England

Original application March 4, 1942, Serial No.
433,322. Divided and this application July 17,
1943, Serial No. 495,097. In Great Britain
June 10, 1941

2 Claims. (Cl. 42—75)

1

The present invention relates to improvements in automatic guns and in particular to that type of automatic guns known as sub-machine guns, and the object of the invention is to provide improved means of assembling together the gun body and butt, this application being a division of application Serial No. 433,322, filed March 4, 1942.

A further object of the invention is to provide gun body and butt assembling means which will ensure that a safe and strong connection is made between the butt and gun body when these parts are joined, but which will also enable the said parts readily to be disconnected when desired.

According to this invention there is provided means for assembling the body and butt of an automatic firearm, such means comprising a butt holder of generally cylindrical form into which is adapted to fit the rear end portion of the tubular gun body and which butt holder has a transverse closure wall provided with an annular groove adapted to receive the rear end of the said gun body, and a securing pin adapted to be passed through registering holes provided in the said butt holder and the part of the gun body therein in order rigidly, but detachably, to secure the said gun body and butt holder together.

The accompanying drawings show by way of example an embodiment of the invention.

Figure 1 is a part longitudinal sectional side and part elevational view of an automatic gun embodying this invention;

Figure 2 is a view in longitudinal sectional elevation of the rear end of the gun body;

Figure 3 shows in elevation the securing bolt serving for connection of the gun body with the butt holder;

Figure 4 is a side sectional elevation of the butt holder; and

Figure 5 is a side elevation showing the rear part of the gun body assembled with the butt holder and butt.

Referring to the drawings, the gun comprises a barrel 1 surrounded, in the case illustrated, by a cooling jacket 2, this barrel being rigidly connected with a gun body 3 which is of circular form in cross-section. The usual rearsight 4 is secured to the gun body or casing 3 and provision is made in the lower part of the gun body for attaching a magazine 4 of any suitable design. For example, a holder 6 may be provided for this purpose at the lower side of the gun body 3, to receive the magazine 5 which is held in the holder 6 by a suitable catch 7.

The gun body is rigidly but removably con-

nected at its rear end to a butt holder 8 in a manner to be described, and this holder is in turn connected with a butt 9 of any convenient known form.

5 The butt holder 8 accommodates the trigger mechanism, indicated generally by reference 10 in Figure 1, and carries the trigger guard.

Figures 2 to 5 show the form of the rear part of the gun body 3 and the manner of its connection with the butt holder 8. The rear end of the body 3 is of circular cross-section, and is provided with a hole 14 in its wall (Figure 2). The butt holder 8 is of generally cylindrical sleeve-like form and has, at one end, a circular transverse wall 21 in which is formed coaxially an annular groove 15 as shown in Figure 4 for the reception of the rear end of the cylindrical tubular gun body 3. A transverse hole 16 is formed in the circular end wall 21 of the butt holder 8 on a chord of the circle so that after the end of the gun body 3 has been inserted in the groove 15, and the hole 14 in the gun body has been brought into register with the transverse hole 16 in the end wall of the butt holder, a securing pin 17 (shown separately in Figure 3) may be passed through these holes 14 and 16 firmly to connect the two parts 3 and 8 together.

10 The pin 17 is secured in the holding position by a spring loaded plunger 18 (Figure 3) engaging in a recess in one end of a groove 17' in a flat side 24 provided on the head 25 of the pin 17, such pin and spring being accommodated in a housing formed in a suitable projection 19 (Figure 5) on the butt holder 8. The inner end of the groove 17' limits the outward movement of the pin 17 and prevents it accidentally falling from the butt holder. A rigid and sturdy connection is thus obtained at that part of the gun where deformation has been found most likely to occur in guns of known construction.

15 The butt 9 is secured to the butt holder 8 in any suitable and convenient way, and is provided internally with a hollow guide tube 20 for a recoil rod 22 (engaging the breech block 12) and spring 13, and this guide tube projects into and through a hole in the otherwise closed end of the butt holder 8.

20 At its lower part the butt holder 8 is provided with an opening or slot 23 for the insertion of the trigger mechanism within the butt holder.

I claim:

1. Means for assembling together the body and butt of a firearm having a cylindrical tubular body, said means comprising a butt holder of cylindrical sleeve form constructed to receive in

one end thereof and to embrace in a close fit the rear end portion of said tubular body and to receive in its other end the front end of the butt, a transverse circular closure wall disposed across the said butt holder nearer the butt end than the body end thereof, said wall having in its surface facing towards the body end of the butt holder an annular, axially open groove shaped to receive and to position the rear end portion of said tubular body, the said butt holder and tubular body being provided with transverse holes on a common chord of the cylindrical tubular body and the cylindrical sleeve so as to register with one another when the said tubular body and butt holder are properly interfitted, a locking pin passing through the said holes in the butt holder and body when these holes are in register, and means for securing the said locking pin in the said registering holes including a spring urged securing element carried by the butt holder in a position to engage the locking pin for preventing the same from being unintentionally withdrawn in an end-wise direction.

2. A firearm having a butt, a tubular gun body and a butt holder for detachably connecting said butt to said gun body, said butt holder being of

generally cylindrical tubular form and constructed to receive and hold in the opposite end portions thereof the rear end portion of said gun body and the forward end of said butt, respectively, and including between its ends a transverse wall provided in its surface facing towards the body end of said butt holder with a deep annular axially open groove shaped to receive there-in the rear end of the tubular gun body, and a securing pin passing through registering holes provided respectively in the gun body and butt holder for the purpose of locking the butt holder and gun body together.
